UNITED STATES PATENT OFFICE.

GEORGE E. SPOFFORD, OF NEW MARKET, NEW HAMPSHIRE, ASSIGNOR TO DRAPER COMPANY, OF HOPEDALE, MASSACHUSETTS, A CORPORATION OF MAINE.

SLASHER.

1,130,642.

Specification of Letters Patent. Patented Mar. 2, 1915.

Application filed June 14, 1913. Serial No. 773,596.

To all whom it may concern:

Be it known that I, GEORGE E. SPOFFORD, a citizen of the United States, residing at Newmarket, county of Rockingham, and 5 State of New Hampshire, have invented an improvement in Slashers, of which the following description, in connection with the accompanying drawings, is a specification, like letters on the drawings representing 10 like parts.

The invention to be hereinafter described relates to slashers for treating warp yarns or threads and winding them upon a beam to be afterward placed in the loom, and 15 more particularly it has reference to means for insuring a proper relative position of the warp threads as they are wound upon the beam.

As well understood by those skilled in 20 the art, the slasher is designed to size or treat each thread of the warp, to dry the sheet of warp after sizing, and then wind the dried sheet of warp onto the warp-beam in such manner that the threads will properly 25 unwind therefrom and pass to the shed forming and cloth making devices during the weaving operation. To these ends the warp threads from the desired number of section beams are led through the sizing 30 device and thence to the drying medium, such as heated cylinders or drums, and, as the sizing and drying operations tend to cause the threads to stick together, certain splitting or separating bars are used to divide 35 the dried warp horizontally into several sheets. The divided warp is then passed through the slasher comb, the teeth of which divide the warp into a series of flat bands or "sheaths", as they are termed, each band 40 or sheath being formed of a plurality of warp threads arranged one above the other in a substantially vertical plane, and the several bands or sheaths thus travel toward the beam in substantially vertical parallel 45 planes. Since the axis of the beam is horizontal, each band or sheath must turn through an angle of substantially 90° in order that the threads may be wound upon the beam side-by-side in a single sheet.

50 From the slasher comb the warp passes between evener or smoother bars and then about tension rolls from which it is delivered to the beam in the form of a single sheet.

Between the slasher comb and the warp beam, however, the warp threads are liable 55 to become relatively disarranged or to roll over one another so that one or more threads on the warp beam may be crossed or "overlaid" by others. As a result of this irregular winding much trouble is frequently experienced 60 when the beam is unwound in the loom, all as well understood by those skilled in the art.

The aims and purposes of the present invention are to provide means whereby the 65 objectionable irregular arrangement of the warp threads on the warp beam may be prevented and the warp threads be maintained in proper relative position as they pass to and are wound upon the beam, all as will 70 best be made clear from the following description and accompanying drawings of one form of means for carrying the invention into practical effect, it being understood that features of structure and details may 75 be modified and changed within the true scope of the actual invention which is defined by the claims.

In the drawings:—Figure 1 is front or end view of a slasher looking toward the 80 right, Fig. 2, unnecessary details and parts being omitted for better exploitation of the invention; Fig. 2 is a section on the line 2—2, Fig. 1; Fig. 3 is a detail showing features of the present invention in side elevation on an enlarged scale, and Fig. 4 is a cross-section showing one form of the arranging comb that may be used and its preferred relation to the warp threads.

The general character, construction, and 90 operation of the slasher may be the same as now in general use and being well understood by those skilled in the art, it will not be necessary to show and describe the section beams from which the warp threads 95 are taken, the liquid or sizing device, nor the means for drying the treated threads. From these devices of the slasher the sized and dried warp threads are guided in usual manner by the guide rolls 2, 3, and 4, Fig. 100 2, which may be appropriately sustained by the slasher frame 1, to the splitting or separating bars 5, 6, 7, of appropriate number, as usual, by which the warp is divided horizontally 105 into the desired number of sheets. Only three of these splitting or separating

bars are shown, but it is to be understood that the invention is not restricted in this respect, and that any appropriate number may be employed to properly separate the 5 warp threads, and such bars may be supported in any desired manner, as from the main frame 1 of the machine.

The slasher comb 9 may be of usual construction, preferably of the well known expansion type, having the teeth, as shown, 10 which divide the warp into a series of bands or sheaths, the threads of which are substantially in a vertical plane one above the other.

15 Mounted in suitable sustaining means, such as the brackets 10, are the flattening and smoothing bars 11 and 12, two of which are shown, although it is to be understood that any appropriate number of such bars 20 may be employed. From the slasher comb 9 the warp is delivered to the action of the flattening and smoothing rolls which turn or flatten the bands or sheaths into horizontal position, and from the flattening and 25 smoothing bars the sheet of warp passes to the tension rolls 13, 14, 15, as indicated in Fig. 2. These tension rolls may be of any appropriate character and number, and may be supported by any appropriate 30 means. As shown, the roll 13 is of larger diameter than the coöperating rolls 14 and 15 and is sustained rotatably in a suitable bearing 16; while the rolls 14 and 15 are loosely mounted in the slotted ends 17 of 35 the bracket arms 18. The described mounting of the tension rolls is a good and convenient form but any other appropriate supporting means may be employed.

The beam may also be of any desired form 40 and character, suitable for holding the warp wound thereon, and as illustrated comprises the barrel 19 having the heads 20. The warp beam may be appropriately mounted on the shaft 21 sustained in the bearings 22 45 carried by brackets 23 projecting from the main frame, and suitable means may be employed for rotating the beam to wind the warp thereon.

The parts so far described may be all as 50 usual, and since they, as well as the means for rotating the warp beam to wind the warp thereon, are well understood by those familiar with such machines, no further explanation or illustration of such devices is 55 deemed necessary.

As the bands or sheaths of warp threads pass from the slasher comb to and between the flattening and smoothing bars the bands or sheaths are turned into horizontal 60 position, and during this turning movement the threads are liable to become irregularly arranged or to roll over each other to a greater or less extent. This same tendency is present even after the threads have passed 65 between the flattening and smoothing bars

and while they are traveling from such bars to and around the tension rolls and toward the warp beam, so that even should the bands or sheaths turn to horizontal position in the same direction and without disarrangement of the relative position of the warp threads due to said turning movement, such warp threads are still liable to become more or less crossed or irregularly arranged before they reach and are wound upon the 70 warp beam. In either case, and quite regardless of how the warp threads become thus irregularly related as they reach and are wound upon the warp beam, this condition of the warp threads, when the beam is 75 placed in the loom, forms "draws" which interfere seriously with the proper weaving operation, and one of the purposes of the present invention is to provide means to effectively prevent the occurrence of such 80 irregularity and insure that the threads shall be wound upon the warp beam in a single sheet and in uniform order side by side. As one form of means to these ends 85 the present invention contemplates separating the warp threads horizontally by a comb disposed closely adjacent the warp beam, and after the threads have passed the tension rolls, so that no matter how much 90 crossing or irregularity of threads may have 95 occurred between the slasher comb and the last of the tension rolls, the comb acting upon the threads just before they pass onto the warp beam, will insure their uniform arrangement side by side as they are wound 100 upon the beam. In the form of the invention shown, the said comb, which for identification may be referred-to as the arranging comb, is mounted to maintain its relation with the sheet of warp as the warp 105 beam increases in diameter and is preferably movable to and from operative position to facilitate doffing, as will hereinafter more fully appear.

The arranging comb comprises the comb bar 24 from which project the teeth 25, Figs. 2, 3, and 4, the said teeth being suitably spaced apart to receive between them one or more warp threads 26. The arranging comb is sustained in close proximity to the warp beam and between it and the tension rolls, so that, just as the warp passes onto the beam the teeth of the comb will separate and arrange the warp threads in uniform relation side by side, and as one form of means for thus sustaining the arranging comb the end portions of the comb bar 24 may be extended to engage bearings 27 in the arms 28, pivotally supported from the machine frame. In the construction shown as a good practical embodiment of the invention, the supporting arms 28 are secured by means of a set screw 31 or otherwise, to a rock shaft 29 mounted in suitable supports 30 rising from one of the flatten- 115 120 125 130

ing and smoothing bars, the construction being such that the arranging comb may be sustained in close proximity to the warp beam 19 and between it and the tension rolls.

As the warp is gradually wound upon the beam, the latter increases in diameter, so that the path of the warp from the tension rolls to the beam varies in inclination or direction, and the described mounting of the arranging comb upon the swinging supporting arms 28 thus permits the comb to move with the sheet of warp in a direction transverse to the axis of the warp beam and maintain its operative relation with the warp sheet during the variations in diameter of the load on the beam. It is to be understood, however, that while the particulars of structure thus far described furnish a good practical form of the invention, the invention itself is not restricted thereto, but in its broad character embraces various modifications and equivalent means for sustaining the arranging comb in operative relation to the warp closely adjacent to the warp beam.

In doffing, it is desirable that the arranging comb be moved out of operative position and to this end the supporting arms may be turned upward, as indicated by the dotted lines, Fig. 2. At such time, an arm or lug 32 secured to the rock shaft 29, as by the set screw 33, Figs. 1 and 3, contacts with an appropriate stop, such as the edge of the flattening and smoothing bar 12, to maintain the arranging comb in raised or inoperative position. Obviously the means for permitting the arranging comb to be moved from operative position during doffing may be variously formed.

The teeth of the arranging comb are preferably provided with the pointed ends whereby as the comb is brought into operative position the teeth will more readily insinuate themselves between the threads of the warp.

It occasionally happens that fluff or a knot may be carried by a warp thread as it approaches the arranging comb, and since this comb is comparatively fine such fluff or knot may not readily pass between the teeth of the comb. To meet this condition and guard against breakage of threads, the comb is preferably arranged or adjusted so that when in operative position, as indicated by Figs. 3 and 4, the face 35 of the teeth 25 will be at an obtuse angle to the path of approach of the warp, see Fig. 4, the construction and arrangement being such that should a knot or piece of fluff or the like be carried by a warp thread against the inclined face 35 of the teeth, it will cause the warp thread to move outwardly until the knot or fluff or the like passes over the end of the teeth, whereupon the thread will

again resume position between the teeth of the comb without causing breakage of a warp thread.

The arranging comb is shown as preferably comprising the bar 24 and attached teeth 25, but it is to be understood that the invention is not restricted thereto and that any preferred comb may be employed. In the illustrated form of the invention, the comb rests or bears upon the sheet of warp threads and is preferably supported thereby so that as the beam load increases in diameter the comb will be moved in a direction substantially transverse to the axis of the beam, its teeth being thus maintained in intersecting relation with the warp sheet as the path thereof changes. As the teeth of the comb are preferably to remain in substantially the described angular relation with the sheet of warp, it is desirable that means be employed to control this angular relation throughout the winding operation. Various means may be employed to this end, and as one convenient and practical form thereof, the present invention contemplates a controller or bar connected to the arranging comb and bearing upon the warp sheet.

In the form of the invention illustrated, the controller comprises a rod or bar 36 extending to a more or less extent transversely of the sheet of warp and connected to the arranging comb. In the present instance this connection comprises the split sleeves 37 which embrace the comb bar 24 to which they may be adjustably clamped by the set screws 38. The controller 36 is adjustably secured to the sleeves 37 and to this end is preferably formed with side arms 39 and end extensions 40 which engage suitable sockets in the split sleeves 37 to which they may be adjustably secured by suitable means, such as set screws 41.

From the construction described it will be noted that by proper adjustment of the split sleeves 37 on the comb bar and the controller 36 with respect to the split sleeves, the angular relation of the comb teeth to the path of travel of the warp may be adjusted and maintained with relation to the sheet of warp throughout the winding operation in a manner to insure the proper passage of any knot or fluff carrying warp thread over the end of the comb teeth.

From the construction described as one form of the present invention, it will be noted that the warp threads, just prior to their delivery to the warp beam and after the various means for arranging the warp in a single horizontal sheet in the slasher have acted, are separated and arranged in parallel relation side by side, thus avoiding any liability of overlaying as the threads are wound upon the beam and the resulting objectionable "draws" when the threads

are taken from the beam in the loom. It will be noted also that in preparing the warp for "drawing in," that is passing the individual threads in regular order through the heddles or shed forming means, the lease forming comb may be engaged with the warp closely adjacent the arranging comb before the warp is taken from the slasher, thus insuring that the arrangement and order of threads presented to the drawing in device by the lease comb shall be the same arrangement and order of threads as actually exists on the warp beam itself.

What is claimed is:—

15 1. In a slasher, the combination of a warp beam on which the warp threads are to be wound, means for arranging the warp threads in sheet form to be wound upon the beam, a comb, means for positioning the comb upon the sheet of warp threads between the warp beam and said arranging means, and permitting said comb to freely move with the sheet of threads in a direction transverse to the axis of the warp beam 25 as the diameter of the load increased.

20 2. In a slasher, the combination of means for forming the warp threads in a single sheet, a beam on which the sheet of warp threads is to be wound, and means resting upon and movable with the sheet or warp threads in a direction transverse to the axis 30 of the beam as the load upon the beam increases in diameter for directing the threads of the sheet in parallel relation side by side 35 as they are wound on the warp beam.

40 3. In a slasher, the combination of a beam, means for delivering a single sheet of warp threads to be wound upon said beam, a comb bar supported by and above the sheet of warp threads between said means and the beam and having teeth for separating and directing the warp threads in parallel relation side by side as they are wound upon said beam, and means for holding the comb 45 in the said position and permitting the comb to be moved away from said position.

45 4. In a slasher, the combination of means for arranging warp threads in a sheet, a beam on which said sheet of warp thread is to be wound, a comb between said means and the beam for arranging the warp threads in parallel relation and directing them in such undisturbed condition to the beam, and means engaging the comb to position it above and to be moved by the sheet 50 of warp threads as said sheet changes inclination during the winding operation.

55 5. In a slasher, the combination of means for arranging warp threads in sheet form, a beam upon which the sheet of threads is to be wound, a comb supported by the warp threads between said means and beam and having teeth intersecting the path of travel 60 of the sheet of warp threads and means for maintaining the comb in said position and

permitting the comb to be moved away from the plane of movement of the warp threads.

6. In a slasher, the combination of means for arranging sized and dried warp threads in single sheet form, a beam on which such warp sheet is to be wound, and a comb disposed above and supported by the sheet of warp threads between said means and beam for directing the threads in uniform order side by side onto said beam.

7. In a slasher, the combination of a beam, means for arranging sized and dried warp threads in a single sheet form to be wound upon said beam, a comb, and means for supporting the comb upon the warp threads 80 with the teeth thereof in the path of movement of the sheet of warp threads between the said means and beam as the said sheet changes its path of movement during the winding operation.

8. In a slasher, the combination of a beam, means for forming sized and dried warp threads in a single sheet to be wound upon said beam, a comb, pivotally mounted arms for holding the comb in position supported 90 by and above the warp threads close to the beam and permitting it to move uniformly with the sheet of warp threads in a direction transverse to the axis of the beam as said sheet changes its path of travel during 95 the winding operation.

9. In a slasher, the combination of a beam, means for forming sized and dried warp threads in a single sheet to be wound upon said beam, a comb disposed above and supported by the warp threads, pivotally mounted arms carrying the comb at their free ends in position close to the beam and permitting it to be moved by and with the sheet of warp threads in a direction transverse to the axis of the beam as said sheet changes its path of travel during the winding operation, and permitting said comb to be moved to inoperative position for doffing, and means for sustaining said comb 110 in such inoperative position.

10. In a slasher, the combination of a beam, means for arranging sized and dried warp threads in a single sheet to be wound upon said beam, a comb disposed above the 115 sheet of warp threads between said means and beam, and a controller connected to the comb and resting upon the sheet of warp threads at one side of said comb.

11. In a slasher, the combination of a 120 beam, means for arranging the sized and dried warp threads in a single sheet to be wound upon said beam, a comb, arms pivotally connected to the machine frame for holding said comb between said means and beam, and a controller bearing against the sheet of warp thread at one side of said comb and connected thereto.

12. In a slasher, the combination of a beam, means for arranging the sized and 125

dried warp threads in a single sheet to be wound upon said beam, a comb, arms carrying said comb and pivotally mounted at one end, a controller connected to said comb and resting upon the sheet of warp threads close to the warp beam.

13. In a slasher, the combination of a beam, means for arranging the warp threads in sheet formation to be wound upon said beam, a comb having teeth and disposed above and supported by the sheet of warp threads between said means and beam for directing the threads in uniform order side by side onto said beam, and means for adjusting the angular relation between the comb teeth and path of travel of the warp threads.

14. In a slasher, the combination of a beam, means for arranging sized and dried warp threads in a single sheet as they are wound upon said beam, a comb disposed above the sheet of warp threads between said means and beam, pivotally mounted arms for holding said comb, a controller adjustably connected to said comb and bearing upon the sheet of warp threads nearer the said beam than the comb.

15. In a slasher, the combination of a beam, means for forming the sized and dried warp threads in a single sheet to be wound upon said beam, arms pivotally connected to the machine frame, a comb carried by said arms above the sheet of warp threads between said means and beam for arranging the warp threads in parallel relation side by side as they are wound upon said beam, and a controller having a part extending transversely of and resting upon the sheet of warp, and means for adjusting the relation of the comb and controller.

16. In a slasher, the combination of a beam, means for directing warp threads to be wound on said beam, a comb, pivotally mounted arms carrying said comb at their free ends in position to rest upon the warp threads, and means connected to the comb

and engaging the warp threads for determining the angle of the comb teeth to the path of warp thread movement.

17. In a slasher, the combination of a beam upon which the warp threads are to be wound, arms pivotally mounted at one end, and a comb carried by the free ends of said arms and supported by the warp threads in close proximity to the warp beam.

18. In a slasher, the combination of a frame, a warp beam supported thereby, means for delivering the warp threads in sheet form to said beam, a comb disposed between said means and warp beam, and means bearing upon the warp threads and connected to the comb for supporting the comb in relation thereto.

19. In a slasher, a warp beam, means for arranging the warp threads in a single sheet to be wound upon the beam, a comb, pivotally mounted arms carrying the comb at their free ends in position between said means and warp beam with the comb supported by the sheet of warp threads and adapted to be turned about their pivotal mounting to carry the comb upward and away from the warp threads, and a stop to hold said arms and comb when turned upward.

20. In a slasher, the combination of a warp beam, means for arranging the warp threads in a single sheet to be wound upon said beam, a comb bar adapted to rest upon and be supported by the sheet of warp threads between said means and warp beam with the teeth of the comb projecting between the warp threads, and arms carrying said comb bar.

In testimony whereof, I have signed my name to this specification, in the presence of two subscribing witnesses.

GEORGE E. SPOFFORD.
